ABSTRACT: A single-gun, plural-beam-type color television picture tube in which three electron beams representing different color signals are focused by a single lens, after which two of the beams diverge. The two divergent beams are reconverge by convergence deflecting means so they will intersect with the third beam at a common point at a beam-selecting grid, from which point the beams again diverge to impinge on respective color phosphors which together represent a color picture element. Misconvergence, i.e., reconvergence of the two divergent beams to a point other than to the common point of intersection with the third beam, which arises from manufacturing inaccuracies such as the misorientation of the convergence deflecting means with respect to the single electron gun of the tube, or the misorientation of the aperture of the beam-generating means of the tube, is compensated for by the provision of convergence deflecting means which exerts upon at least one of the divergent beams an electric, or Coulomb, force which varies in its direction in accordance with the position at which the beam enters and passes through the convergence deflecting means. Thereby, variations in the direction of the electric force compensates for variations in the position at which the beam is introduced to eliminate the misconvergence which arises from the above-mentioned manufacturing inaccuracies.

MISCONVERGENCE COMPENSATION FOR SINGLE-GUN, PLURAL-BEAM-TYPE COLOR TV PICTURE TUBE

This invention relates generally to color picture tubes of the single-gun, plural-beam type, and particularly to tubes of that type in which the plural beams are passed through the optical center of a common electron lens by which the beams are focused on the color phosphor screen of the tube.

A single-gun, plural-beam color picture tube exists, in which three different cathodes produce three different electron beams that respectively correspond to the three primary colors. An example of such a tube is disclosed specifically in a copending U.S. application Ser. No. 697,414 filed Jan. 12, 1968, Pat. No. 3,448,316 and having a common assignee herewith. The cathodes in such a tube are arranged in a horizontal row, so that the three electron beams start out side by side. Shortly after leaving the gun, the three beam intersect at a common point in the center of a single electrostatic lens which serves to focus all three beams upon a color screen. However, after leaving the focusing lens, the three electron beams diverge. The center beam continues in a central straight line, but the two beams on both sides diverge sideways, i.e., outwardly, away from the path of the central beam, and must therefore be reconverged by pairs of convergence deflection electrodes to which a convergence deflection voltage is applied. This convergence causes all three beams to intersect at a common point where they pass through a beam-selecting grid, after which they again diverge to impinge on the respective color phosphors constituting a color picture element on the color screen.

The pairs of convergence deflection electrodes in the picture tube shown and described in this copending application comprise plates which are disposed in parallel with each other. Since the electrodes, i.e., plates, are flat and parallelly disposed with respect to each other, the direction of the electric, or Coulomb, force applied to the electron beams is always at right angles to the surface of these plates. As a result, misconvergence, i.e., reconvergence of the two divergent beams to a point other than the common point of intersection with the third beam, can be prevented only if the plural beam (i.e., the beam comprising the three beams mentioned above) always is introduced into convergence deflection electrodes at a predetermined position. If, because of manufacturing inaccuracies, this predetermined position is deviated from by a shift of the beam with respect to the plates or by another discrepancy, which causes at least one of the two diverging beams to be displaced in a direction parallel to surface of the flat plates, misconvergence is produced, which is not corrected by suitably compensating for the shift or other discrepancy. The manufacturing inaccuracies which may cause this misconvergence include misorientation of the convergence deflecting means with respect to the single electron gun or misorientation of the aperture of the beam-generating means in such a picture tube.

Accordingly, it is an object of this invention to provide a single-gun, plural-beam color picture tube of the type described in which, when a discrepancy develops in the position at which the beams enter the convergence-deflecting means, this discrepancy is compensated to thereby prevent misconvergence.

It is another object of this invention to provide a single-gun, plural-beam color picture tube of the type described having a convergence deflecting means of relatively simple structure provided between the focusing lens and the beam-selecting grid, or mask, for causing the beams emerging from the focusing lens along divergent paths to converge to a point at the grid, or mask.

In a color picture tube of the type described above, the present invention provides convergence-deflecting means which exerts upon at least one of the diverging beams an electric force whose direction varies with the position at which it enters the convergence deflecting means, whereby any variation in the position at which it enters is corrected, or compensated for, by a variation in the direction of the electric force which is applied to it, such being to correct for misconvergence which would otherwise result.

The above, and other objects, features and advantages of the invention, will be apparent in the following detailed description of illustrative embodiments thereof which is to be read in connection with the accompanying drawing.

5 In the drawing:

FIG. 1 is a horizontal sectional view schematically showing a single-gun, plural-beam color picture tube such as disclosed in the above-mentioned application;

10 FIG. 2 is a cross-sectional view, also schematic, taken along the line I—I in FIG. 1, which illustrates the condition when there is no discrepancy in the position at which the electron beams enter the convergence-deflecting means;

15 FIG. 3 is a view identical to the one shown in FIG. 2 which illustrates the condition when there is a discrepancy in the position at which two of the electron beams enter the convergence-deflecting means;

20 FIG. 4 is another view identical to the one shown in FIG. 2 which illustrates the condition when there is a discrepancy in the position at which one of the electron beams enters the convergence-deflecting means;

25 FIG. 5 is a cross-sectional view, similar to the cross-sectional view of FIG. 2, also schematic, showing electron beam convergence deflecting means for use in a color picture tube identical to the one shown in FIG. 1 except wherein the electron beams are disposed within the tube in a delta formation;

30 FIG. 6 is a perspective view schematically showing an electron beam convergence deflecting means, constructed in accordance with the teachings of this invention, for a single-gun, plural-beam color picture tube such as shown in FIG. 1;

FIG. 7 is a cross-sectional view, taken along the line II—II in FIG. 6, which illustrates the condition when there is no discrepancy in the position at which the electron beams enter the convergence deflecting means;

35 FIG. 8 is a cross-sectional view, identical to the one shown in FIG. 7, which illustrates the condition when there is a discrepancy in the position at which two of the electron beams enter the convergence-deflecting means;

40 FIG. 9 is a cross-sectional view, identical to the view of FIG. 7, which illustrates the condition when the electron beams are disposed in a delta formation as they are in FIG. 5;

45 FIG. 10 is a view, identical to the one shown in FIG. 8, of electron beam convergence-deflecting means constructed in accordance with and illustrating another embodiment of this invention; and

50 FIG. 11 is a view, similar to the one shown in FIG. 8, of still another electron beam convergence-deflecting means constructed in accordance with and illustrating still another embodiment of this invention.

Throughout these Figures the same reference characters are used to refer to the same elements.

Referring to the drawings in detail, and initially to FIG. 1 thereof which schematically shows a cross-sectional view of a single-gun, plural-beam color picture tube such as disclosed in the aforementioned copending U.S. application, it will be seen that a single electron gun A of such a color television picture tube comprises three cathodes K_R, K_G and K_B, which produce the electron beams B_R, B_G and B_B respectively for the red, green and blue signals of such a tube. These three beams, after leaving their respective cathodes, pass through respective apertures g_{1R}, g_{1G} and g_{1B} formed in a first grid G₁. Then, they proceed through corresponding respective apertures g_{2R}, g_{2G} and g_{2B} formed in a second grid G₂. The apertures of the grids G₁ and G₂ serve the conventional beam-forming function. As the electron beams leave the second grid G₂, they then pass through three open-ended tubular grids or electrodes G₃, G₄ and G₅, in that order. The grid G₄ and electrodes G₃ cooperate to form a relatively weak auxiliary lens L' by which the parallel beams are made to converge at the optical center of a main lens L formed by electrodes G₃, G₄ and G₅ and which serves to focus all three beams upon the phosphor screen S on the faceplate of the tube.

75 After the three beams B_B, B_G and B_R leave focusing lens L, center beam B_G continues in a straight line coincident with the

optical axis of the lens. The beams B_B and B_R , however, diverge away from the center beam B_G . Accordingly, convergence deflecting electrodes generally designated F are provided for the purpose of converging the outer beams to intersect at a common spot with the center beam so that all three beams pass through the same aperture between individual grid wires g_p of the beam-selecting grid or mask G_p . Thereafter the beams again diverge so that the red signal beam B_R goes on to strike the red phosphor stripe S_R , the blue signal beam B_B goes on to strike the blue phosphor strip S_B and the green signal beam B_G goes on to strike the green phosphor stripe S_G of a common color television picture element.

As indicated in FIG. 1, the first grid G_1 may receive a static potential of 0 to minus 400 volts, for example about minus 400 volts, the second grid G_2 may receive a static potential of 0 to 500 volts, for example about 500 volts, while the center lens element G_4 may receive a potential of 0 to 400 volts, for example about 400 volts. The two outer lens elements G_3 and G_5 are connected to a potential V_p which is at or near the anode potential (13 to 20 kv.) of the tube. The first grid G_1 performs the intensity modulation function, and therefore also has a signal voltage applied thereto. As a result, the voltage distributions between the respective electrodes and cathodes and the respective lengths and diameters thereof, may be substantially identical with those of a unipotential-single-beam type electron gun which is constituted by a single cathode and first and second, single-apertured grids. A voltage V_M is applied to the grid wires g_p of the beam-selecting grid G_p .

Moreover, in the conventional manner, the electron beams are swept horizontally and vertically across screen S to produce the usual cathode-ray tube raster. In FIG. 1, the electron beams B_B , B_G and B_R are swept from one extremity of the screen S to its other extremity. The horizontal and vertical deflections necessary to produce the picture raster are of course accomplished by conventional deflection yokes D mounted outside the neck N of the picture tube.

In order to converge the electron beams, the electron beam convergence deflecting means F comprises outer electrodes or flat plates, Q and Q', and inner electrodes or flat plates P and P' which are spaced from each other and respectively spaced inwardly from the plates Q and Q'. The inner electrodes P and P' are maintained at a higher potential than either of the outer electrodes Q and Q'. Since the electrodes P and P' are of the same potential, the green signal beam B_G is not deflected in passing therebetween. The blue signal beam B_B passes between the outer electrode Q and the inner electrode P, while the red signal beam B_R passes between the outer electrode Q' and the inner electrode P'. Accordingly, the divergent beams B_B and B_R are deflected inwardly by electric, or Coulomb, forces E and E' (see FIG. 2), which are given by the respective voltage gradations between their respective pairs of electrodes Q, P and Q', P', to intersect with beam B_G at a common point on the beam-selecting grid G_p .

In order to maintain the necessary high potential upon the inner electrodes P and P', these electrodes are connected jointly to the highest potential of the tube, i.e., the anode voltage V_p .

In order to maintain the outer electrodes Q and Q' at a somewhat lower potential than the inner electrodes P and P', the outer electrodes Q and Q' are provided with potential V_q . It is sufficient that this potential V_q is lower than the anode voltage V_p by about 200-300 volts.

Referring now to the convergence-deflecting means F in detail, by means of electric force E applied to beam B_B by electrodes P and Q' and by means of electric force E' applied to beam B_R by electrode P' and Q', beams B_B and B_R are deflected toward the central axis B_G of the color picture tube. This axis B_G lies in the path defined by the beam B_G , which beam, accordingly passes therewith. The beams B_R , B_G and B_B , as shown in FIG. 2, are disposed in line with the horizontal axis x (i.e., they are aligned to meet if deflected at right angles to the central axis B_G) and are introduced into the electrodes F at equal distances from each other. Accordingly, the conver-

gence deflecting means F causes beams B_R , B_G and B_B to intersect at a common point on the beam-selecting grid G_p .

When the beams are positioned as shown in FIG. 2, the three beams can be made to intersect accurately at the above-mentioned common point by adjusting the intensity of the electric forces E and E' and by adjusting the potential V_q , because both of the electric forces E and E' are in the direction of the horizontal axis x and are directed toward the beam B_G .

On the other hand, when the coaxially disposed convergence deflecting means F and the single electron gun A are misaligned because one is rotated, i.e., angularly displaced, out of proper position with respect to the other, because of manufacturing inaccuracies or the like, the electric forces E and E' are prevented from being directed toward the beam B_G because, as can be seen in FIG. 3, the line a, along which beams B_B , B_G and B_R are arranged, is displaced from axis x by an angle α . Consequently, beams B_R , B_G and B_B are at best converged in a line along the vertical axis y, meeting at right angles with the horizontal axis x and passing through the central axis B_G , when forced to converge in the direction of the forces E and E'. They are not converged at the above-mentioned common point. In addition, the respective distances between beam B_B and axis x and between beam B_R and axis x gradually increases as the beams go through the convergence deflecting means F toward the beam-selecting grid G_p . In short, convergence deflecting electrodes F, shown in FIGS. 2 and 3, cause deflection of the beams only in the direction of the horizontal axis x. They do not cause the beams to be deflected in the direction of the vertical axis y.

FIG. 4 is a cross-sectional view identical to the one shown in FIG. 3 but one in which the position of the beams, at entry and upon passing through the deflecting means F, is somewhat different than the position of the beams in FIG. 3. In this view, beams B_G and B_R enter and pass through the deflecting means at a predetermined position along the horizontal axis x, but the beam B_B enters and passes through at a position on a line displaced by an angle α from the axis x, as shown in FIG. 3. The deflecting means F can focus the beams B_G and B_R respectively, but it cannot focus beam B_B . This is because there is no component of electric force E in the direction of axis y to shift the beam B_B in that direction.

FIG. 5 is a cross-sectional view, similar to FIG. 2, of electron beam convergence deflecting means for a single-gun, plural-beam color picture tube, such as disclosed in the aforementioned copending application, having arrays of beam-emitting cathodes and color phosphor respectively disposed in a delta formation. In this figure, the common inner electrode P'' of the convergence deflecting means F may be in the form of a tube having a triangular, or deltoid, cross section which is coaxial with the optical axis of the focusing lens L, and which has three flat sides arranged parallel to the flat plates Q, Q' and Q'' which are spaced outwardly therefrom. In this case also, when voltage V_p is applied to inner electrode P'' and a relatively smaller voltage V_q is applied to plates Q, Q' and Q'', the respective beams passing therebetween are deflected inwardly toward the central axis for convergence at a common point on the beam-selecting grid G_p .

In addition, color screen S (reference being had to FIG. 1) has, in this case, delta arrays of color phosphor S_B , S_G and S_R , and the tube has beam-selecting means G_p and beam-generating means respectively provided with apertures and cathodes K_B , K_G and K_R corresponding to said arrays. Consequently, if beams B_B , B_G and B_R pass through a position on the axis lines x_1 , x_2 and x_3 , which lines intersect at the central line of the color picture tube and are perpendicular to the respective electrode plates Q, Q' and Q'', the electric forces E, E' and E'' applied to the respective beams B_B , B_G and B_R by the electrodes P'' , Q, Q' and Q'' are directed toward a point 0 on the central line. This enables the three beams to be focused on screen S. On the other hand if beam B_G , for example, is biased for some reason from its position on axis x_2 to a position B'_G , because of a discrepancy in the position of apertures g_{1G} and

g_{2C} for example, there is no possibility that the three electron beams B_B , B_G and B_R will converge into the central line of the color picture tube because the electric force E' has no component in a direction at right angles to the axis x_2 .

Stated succinctly, with the convergence deflecting means F shown in FIG. 2 or FIG. 5, it is possible to converge the beams to correct deviations of the beams in the directions of the axis x or the axes x_1 , x_2 and x_3 , but it is impossible to converge the beams to correct deviations of the beams in the directions at right angles with these axes thereby to correct, or compensate for, misconvergence. Consequently, when there is no error in design or assembly it is possible to avoid blooming of the focused beams at a spot, such blooming being caused by spherical aberration coma, or the like. Also it is possible to minimize the radius of the neck of the tube and to make the deflecting power small because the magnetic field effect is good. On the other hand quite accurate design and assembly is required, the allowable error for such being limited to fall within a small range. Manufacturing within this limited range is troublesome.

In accordance with this invention convergence deflecting means F is provided which eliminates the aforementioned troublesome manufacturing requirements and which is designed to effectively correct for any discrepancy in the position at which the electron beams enter the convergence deflecting means and to insure that the plural beams are converged in the vicinity of the phosphor screen, for example at the beam-selecting grid.

FIGS. 6 to 8 illustrate one embodiment of a convergence deflecting means F constructed in accordance with the teachings of this invention for use in a single-gun, plural-beam color picture tube of the type shown in FIG. 1. Such a color picture tube, constructed in accordance with this invention, therefore, is either identical or similar to the tube shown in FIG. 1, except that the structure of the convergence deflecting means F is different. This convergence deflecting means F consists of a pair of cylindrical electrodes P and Q which are coaxially disposed and have different radii respectively. In accordance with this construction, if the positions B_B , B_G and B_R at which the electron beams B_B , B_G and B_R enter the convergence-deflecting means are arranged at equal intervals along horizontal axis x as shown in FIG. 7 (as they also are in FIG. 2), and if the electric forces E and E' applied to the beams B_B and B_R by the electrodes P and Q are directed toward the central axis B_G , the beams B_B and B_R will be directed toward the beam B_G , so that, as in the case illustrated in FIG. 2, the beams B_B , B_G and B_R will accurately converge at a common point on beam-selecting grid G_p .

If the position B_B , B_G and B_R shown in FIG. 8 at which the electron beams enter into the convergence deflecting means F , are arranged in line a displaced by an angle α from the horizontal axis x , as in the case illustrated in FIG. 3, the direction of electric forces E and E' applied to beams B_B and B_R will not be parallel with axis x , but will be in the direction of the line a and directed toward the beam B_G . As a result, electric forces E and E' not only have components E_x and $E'x$ respectively directed towards the axis x , but also have components E_y and $E'y$ directed toward the axis y , so that, unlike in the case illustrated in FIG. 3, it is possible to converge the three beams accurately at the above-mentioned common point. In addition, it is easy to converge the beams since, as the angle α becomes larger, the components E_x and $E'x$ in the direction of the axis x become smaller and the components E_y and $E'y$ become larger. Furthermore, it should be noted that the directions of the electric forces E and E' gradually change in accordance with the change in the angle α and that this change is made in the direction which provides for the accurate convergence of the beams.

As shown in FIG. 8, the beams B_B , B_G and B_R are converged although they are not all in a line (beam B_R being located at the position B'_R on axis x , similar to its location in FIG. 4) because the beam B_R is deflected in almost the same manner as it is in FIG. 7 and beam B_B is displaced as described above.

FIG. 9 shows convergence-deflecting means identical in construction to the convergence means shown in FIGS. 6 to 8, but in this case it is used for converging electron beams that are disposed in a delta formation such as shown in FIG. 5. In this case, if the beams B_B , B_G and B_R are introduced accurately, i.e., introduced so as to define apexes of an equilateral triangle, into the convergence-deflecting means F and if the electric forces E and E' from plates P and Q are directed toward the center 0 , as in the case shown in FIG. 5, the three electron beams converge. However, for some reason the electron beam B_G is caused to move into position B'_G on line a displaced by an angle α from axis X_2 , the beam B_G will converge with the other two beams B_B and B_R , almost in the same manner as either of the beams B_B or B_R converge in FIG. 8, since electric force E''' applied to beam B'_G has a component $E'''x$ in the direction of axis x_1 and a component $E'''y$ in the direction of axis x_2 .

FIG. 10 shows convergence-deflecting means constructed in accordance with the teachings of this invention and illustrating another embodiment of it. As shown in this figure, the electrodes P and Q respectively are notched, i.e., they have portions removed, along their sides. Accordingly, the single electrode P of the convergence-deflecting means shown in FIGS. 6 through 8 is substituted for a pair of opposing, half-cylindrical electrodes Q' and Q'' . In the case when the electron beams are disposed in the tube in a straight line, this electrode arrangement enables unnecessary portions of electrodes P and Q to be removed since the electron beams are not usually biased very far from horizontal axis x . This simplifies the apparatus. Furthermore, this convergence-deflecting arrangement achieves the same effect as is achieved by the arrangement shown in the FIGS. 6 to 8.

FIG. 11 shows other convergence-deflecting means constructed in accordance with the teachings of this invention and illustrating still another embodiment of it. In this figure, the radial center point O_1 of the electrodes P' and Q' are shifted respectively along axis x so that the electrodes are brought closer together. Also, the electrodes are somewhat flatter i.e., they have less curvature, than those shown in FIG. 10. Consequently, the electric forces E and E' applied respectively to electron beams B_B and B_R have a larger component in the direction of the horizontal axis x as compared to the component they have in the direction of vertical axis y than they have in the embodiment shown in FIG. 10. Since the electric forces E and E' applied to the beams B_B and B_R are introduced on line a meeting at an angle α with the horizontal axis x , they have components E_y and $E'y$ in the direction of vertical axis y at all times. Dependent upon the particular structure of the color picture tube, it is often possible to converge the beams more effectively with this convergence-deflecting means than it is with the means shown in FIG. 10.

The convergence-deflecting means described in detail herein have illustrated the converging of three electron beams only, but it should be understood that any number of beams, for example, 2, 4 or 5, may be converged with apparatus constructed in accordance with the teachings of this invention.

In addition, beam-selecting grid G_p may be a chromatron-type grid (i.e., a line grid), a shadow mask, an aperture grid, any other appropriate device.

Although illustrative embodiments of this invention have been described in detail herein with reference to the accompanying drawings, it is to be understood that the invention is not limited to those precise embodiments, and that various changes and modifications may be effected therein by one skilled in the art without departing from the scope or spirit of the invention as defined in the appended claims.

What is claimed is:

1. A single-gun, plural-beam color picture tube which includes a color screen having in-line arrays of different color phosphors, beam-selecting means provided with apertures corresponding respectively to said arrays, beam-generating means for directing a central electron beam and two side electron beams from in-line sources toward said color screen for

impingement on respective phosphors of each array through the corresponding aperture, single lens means for focusing said electron beams on said color screen and having an optical center through which said beams all are passed with said central beam being coincident with the optical axis of said lens means and said side beams being angled with respect to the optical axis of said lens means so as to enter said lens means along paths that are convergent to said optical axis and to emerge from said lens means along paths that are divergent to said axis, and convergence-deflecting means interposed between said lens means and said beam-selecting means and being operative to deflect said side beams emerging along said divergent paths to converge them with said central beam at an aperture of said beam-selecting means, said convergence-deflecting means comprising inner and outer electrodes which are parallelly curved about said axis and spaced from each other and from said axis so that only said side beams emerging along said divergent paths pass between said inner and outer electrodes, and means for applying different potentials to said inner and outer electrodes, respectively, and thereby

20

establishing an electric field therebetween which exerts on said side beams passing therebetween forces directed substantially radially toward said axis irrespective of the positions at which said side beams enter said electric field.

5. 2. A single-gun, plural-beam color picture tube as described in claim 1, wherein said electrodes are cylinders which are coaxially disposed and which have different radii respectively.

10 3. A single-gun, plural-beam color picture tube according to claim 1, in which an individual set of said inner and outer electrodes is provided for each of said side beams, and said inner and outer electrodes of each set are half-cylindrical with different radii and are coaxial with said optical axis.

15 4. A single-gun, plural-beam color picture tube according to claim 1, in which an individual set of said inner and outer electrodes is provided for each of said side beams, said inner and outer electrodes of each set are part-cylindrical with different radii and have axes that are offset from said optical axis in the direction away from the side of said optical axis at which the respective set of electrodes is disposed.
